UNITED STATES PATENT OFFICE.

GEORGE WILKINSON, OF PROVIDENCE, RHODE ISLAND, ASSIGNOR TO GORHAM MANUFACTURING COMPANY, OF SAME PLACE.

DESIGN FOR SPOONS AND FORKS.

Specification forming part of Design No. 6,969, dated October 28, 1873; application filed August 29, 1873.
[Term of Patent 7 years.]

To all whom it may concern:

Be it known that I, GEORGE WILKINSON, of the city and county of Providence and State of Rhode Island, have originated a new Design in Articles of Silver and Plated Ware for Spoons and Forks, of which the accompanying photograph, with this specification, is a full and complete description—that is to say, the article of spoons and forks, substantially as shown in the said photograph.

I claim—

The design for spoons and forks, substantially as herein set forth.

Witnesses: GEORGE WILKINSON.

J. F. P. LAWTON,

T. A. BARTON.
